UNITED STATES PATENT OFFICE.

FRANK W. MIX, OF TERRYVILLE, CONNECTICUT, ASSIGNOR TO EAGLE LOCK COMPANY, OF SAME PLACE.

DESIGN FOR KEY-BOWS.

SPECIFICATION forming part of Design No. 11,639, dated February 3, 1880.

Application filed December 8, 1879. Term of patent 7 years.

To all whom it may concern:

Be it known that I, FRANK W. MIX, of Terryville, in the county of Litchfield and State of Connecticut, have originated and produced 5 a new Design for a Key, of which the following is a full, clear, and exact description, reference being had to the accompanying drawings, making part of this specification, in which—

- 10 Figure 1 is a side elevation of a key which embodies my design, and Figs. 2 and 3 are like views, showing keys which embody the leading characteristics of said design.
The key proper may be of any ordinary form.
- 15 My design relates only to that portion which is usually termed the "key ring or bow," and which design I term the "Eastlake pattern." Instead of the usual round or oval form for the bow, I make its contour of an angular form—
- 20 as, for example, octagonal. In the central portion of said bow I form a cross of the style known as a "Greek cross," or as "St. Andrew's cross," the contour of which cross is composed of right lines, as shown. This latter device is, in fact, the essential feature of 25 my design, and it may be formed by the opening through the bow, as shown in Fig. 1, or simply a depression of that form upon each side, as shown in Figs. 2 and 3.
- 30 I also form in some cases a raised border, *a*, which surrounds the figure of a cross, and borders the bow, as shown in Fig. 1; but the

other features may be used either with or without said border, at pleasure.

Although I herein describe the key-bow as 35 of an octagonal or angular form, I do not wish to confine myself to that form when referring, as in the second claim, to the central figure alone, as I wish to secure the design for the central figure independent of the contour of 40 the bow.

I am aware that a key is shown in a prior patent in which the central figure is in the form of a fancy Greek cross, the contour of which was composed wholly of curved lines, 45 and I hereby disclaim the same.

I claim as my invention—

1. The design for a key, which consists of the bow having the octagonal contour, the central figure in the form of a cross, and the 50 raised border, substantially as described.

2. In a design for a key-bow, the central figure in the form of a Greek cross, the contour of which is composed of right lines, substantially as shown and described. 55

3. In a key, the design for the bow, of angular contour, and having the cross upon it whose contour is composed of right lines, substantially as described.

FRANK W. MIX.
